SIGNALING SYSTEM

Clarence E. Lomax, Oak Park, Ill., assignor to
Associated Electric Laboratories, Inc., Chicago,
Ill., a corporation of Delaware

Application April 21, 1939, Serial No. 269,140

3 Claims. (Cl. 177—360)

The present invention relates to signaling systems and, more particularly, to series telegraph systems.

A fire alarm system conventionally comprises a dispatcher station, at which fires are reported by box circuits or by telephone, a number of fire stations, at which fire fighting apparatus is kept, and one or more series telegraph circuits extending between the various stations in order to facilitate the transmission of telegraphic messages therebetween.

An object of the present invention is to provide, in a telegraph system of the type noted, improved control apparatus at the various stations for facilitating the sending and the receiving of telegraphic messages in an easy and efficient manner.

Another object of the invention is to provide, in a telegraph system including a number of series telegraph circuits, improved switching apparatus at the various stations for controlling the connection of the sending and the receiving apparatus thereto to the various telegraph circuits and for controlling the completion of alternative telegraph circuits in the event the telegraph lines extending between adjacent ones of the stations are interrupted.

The features of the present invention are illustrated as being incorporated in a signaling system comprising a sending station, a plurality of receiving stations, position equipment being provided at each of the stations, a primary telegraph circuit including a source of current connecting the position equipment at the stations in series circuit relationship, and a secondary telegraph circuit including a source of current connecting the position equipment at the stations in series circuit relationship. The primary telegraph circuit includes a number of primary telegraph lines arranged in series circuit relationship and respectively extending between adjacent ones of the stations; and the secondary telegraph circuit includes a number of secondary telegraph lines arranged in series circuit relationship and respectively extending between adjacent ones of the stations.

In accordance with one feature of the invention, a manually operable sending device and an automatic sending device are provided at the sending station. Also, there is provided at the sending station manually operable switching means operative selectively to associate both of the sending devices with the primary and the secondary telegraph circuits and simultaneously

to associate both of the sending devices with the primary and the secondary telegraph circuits. A receiving device is provided at each of the receiving stations; and a manually operable switch is provided at each of the receiving stations which is operative selectively to associate the receiving device thereto with the primary and the secondary telegraph circuits.

Also, there are provided at the sending station first and second manually operable sending devices respectively normally connected in the first and the second telegraph circuits, and first and second manually operable switches. The first manually operable switch at the sending station is operative to disconnect the first sending device from the primary telegraph circuit and to connect the first sending device in the second telegraph circuit; and the second manually operable switch is operative to disconnect the second sending device from the secondary telegraph circuit and to connect the second sending device in the primary telegraph circuit.

In accordance with another feature of the invention, the position equipment at each of the stations includes primary and secondary switching apparatus respectively associated with the primary and the secondary telegraph circuits, the primary switching apparatus included in the position equipment at adjacent ones of the stations being operable to disconnect the primary telegraph line extending between the adjacent stations from the primary telegraph circuit and to complete an alternative primary telegraph circuit including a ground return connection extending between the adjacent stations; and the secondary switching apparatus included in the position equipment at adjacent ones of the stations being operable to disconnect the secondary telegraph line extending between the adjacent stations from the secondary telegraph circuit and to complete an alternative secondary telegraph circuit including a ground return connection extending between the adjacent stations.

Further features of the invention pertain to the particular arrangement of the circuit elements of the telegraph system, whereby the above-outlined and additional features are attained.

The novel features believed to be characteristic of the invention are set forth with particularity in the appended claims. The invention, both as to its organization and method of operation, together with further objects and advantages thereof, will best be understood by reference to

the following specification taken in connection with the accompanying drawings, in which Figures 1 to 3, inclusive, taken together, illustrate diagrammatically the details of a signaling system having incorporated therein the present invention.

Referring now more particularly to Figs. 1 to 3, inclusive, of the drawings, the signaling system there illustrated comprises a sending station in the form of a dispatcher station, indicated at 100, and a number of receiving stations in the form of fire stations, indicated at 200 and 300, these stations being connected together in series circuit relationship by primary and secondary telegraph circuits respectively indicated at 50 and 60. Position equipment arranged at the stations 100, 200 and 300 are indicated respectively at 110, 210 and 310. Also, the fire station 200 comprises a number of batteries 205, 206 and 207, 208 for respectively supplying current to the primary and secondary telegraph lines 50 and 60, two battery chargers 203 and 204 for maintaining the batteries 205, 206 and 207, 208, respectively, in a charged condition, and a number of key switches K250, K255, K260 and K265 for controlling the connections of the batteries to the primary and secondary telegraph lines and to the battery chargers, in a manner more fully described hereinafter.

The position equipment 110 at the dispatcher station 100 comprises a number of telegraph keys K101, K102 and K117, an automatic sender 118, a printer P102, a number of audible alarm devices A107, A109 and A125, a number of supervisory lamps L112, L123, L124, L126, L127 and L128, a number of protective relays R113, R150, R153, R160 and R162, an impulse relay R120, a test relay R170, a number of thermostatic switches in the form of heat coils 172, 173, 174 and 175, a number of control keys K107, K109, K111, K116, K130, K136, K140, K146, K156, K157, K165, K166, K167, K168, K182 and K186. Preferably, the position equipment at each of the fire stations, with the exception of the position equipment 210 at the fire station 200, is identical to the position equipment 310 at the fire station 300, which position equipment comprises a printer P345, two audible alarm devices A311 and A312, and a number of control keys K313, K316, K320, K330 and K335. The position equipment 210 at the fire station 200 is substantially identical to the position equipment 310 at the fire station 300 and includes, in addition thereto, two control keys K220 and K235.

The connection and arrangement of the signaling system and the position equipment at the various stations will best be understood from a consideration of the description of the operation thereof appearing hereinafter.

The batteries 205, 206 may be selectively connected to the line conductors C270 and C271 of the primary telegraph circuit 50 and to the line conductors C211 and C212 extending to the battery charger 203 by the key switches K250 and K255, respectively. For example, when the key switch K250 is operated away from its normal position in one direction, the positive terminal of the battery 205 is connected by way of the contact 251 thereof to the line conductor C270 of the primary telegraph circuit 50; and the negative terminal of the battery 205 is connected by way of the contact 253 thereof to the line conductor C271 of the primary telegraph circuit 50. On the other hand, when the key switch K250 is operated in the other direction, the posi-

tive terminal of the battery 205 is connected by way of the contact 252 thereof to the line conductor C211 extending to the battery charger 203; and the negative terminal of the battery 205 is connected by way of the contact 254 thereof to the line conductor C212 extending to the battery charger 203. In a similar manner, the batteries 207, 208 may be selectively connected to the line conductors C272 and C273 of the secondary telegraph circuit 60 and to the line conductors C280 and C281 extending to the battery charger 204 by the key switches K260 and K265, respectively.

Assuming that the battery 205 is normally connected to the line conductors C270 and C271 of the primary telegraph circuit 50, a primary series circuit is normally completed including the position equipment 110 at the dispatcher station 100 and the position equipment at the several fire stations. Assuming that the battery 207 is normally connected to the line conductors C272 and C273 of the secondary telegraph circuit 60, a secondary series circuit is normally completed including the position equipment 110 at the dispatcher station 100 and the position equipment at the several fire stations.

The primary series telegraph circuit 50 extends from the positive terminal of the battery 205 by way of the contact 251 of the key switch K250, C270, the contact 222 of the control switch K220, C202, the fuse 181, the winding of the thermostatic switch 174, the resistor 158, the windings of the protective relays R160 and R162, the contact 188 of the key K186, the contact 143 of the key K140, C194, RA121, the winding of the alarm device A107, the telegraph key K101, the winding of the printing magnet PM106, C195, the contact 133 of the key K130, the contact 145 of the key K140, C191, the contact 148 of the key K146, the winding of the thermostatic switch 175, the fuse 182, C302, the position equipment at fire stations, not shown, the fuse 352, the contact 314 of the key K313, the winding of the alarm device A311, the contact 321 of the key K320, the winding of the printing magnet PM347, the contact 324 of the key K320, C355, the contact 332 of the key K330, the fuse 339, C350, the contact 232 of the key K230, C274, the contact 227 of the key K225, C211, and the contact 253 of the key switch K250 to the negative terminal of the battery 205.

The secondary series telegraph circuit 60 extends from the positive terminal of the battery 207 by way of the contact 261 of the key switch 260, C272, the contact 236 of the control key K235, C201, the fuse 179, the winding of the thermostatic switch 172, C198, the contact 138 of the key K136, the contact 132 of the key K130, C192, the winding of the protective relay R150 and R153, the resistor 155, the winding of the thermostatic switch 173, the fuse 180, C301, the position equipment at fire stations, not shown, the fuse 340, the contact 337 of the key K335, the contact 326 of the key K320, the winding of the alarm device A312, the contact 317 of the key K316, the fuse 353, C351, the contact 247 of the key K245, C275, the contact 242 of the key K240, C273 and the contact 263 of the key switch K260 to the negative terminal of the battery 207.

It is noted that the lightning arresters 303, 305 and 304, 306 are operatively associated with

the primary and secondary telegraph circuits at the fire station 300, thereby to give the position equipment 310 thereat lightning protection. In a similar manner, the lightning arresters 178, 179 and 176, 177 are operatively associated with the primary and secondary telegraph circuits at the dispatcher station 100, thereby to give the position equipment 110 thereat lightning protection. Similarly, lightning arresters, not shown, are operatively associated with the primary and secondary telegraph circuits at the other fire stations, including the fire station 200, thereby to give the position equipment thereat lightning protection.

The fuses 339 and 352 in the fire station 300, the fuses 181 and 182 in the dispatcher station 100, and similar fuses, not shown, in the other fire stations, including the fire station 200, are included in the primary telegraph circuit 50 in order to provide the primary telegraph circuit with over current protection. Similarly, the fuses 340 and 353 in the fire station 300, the fuses 179' and 180 in the dispatcher station 100, and similar fuses, not shown, in the other fire stations, including the fire station 200, are included in the secondary telegraph circuit 60 in order to provide the secondary telegraph circuit with over current protection. Also, the thermostatic switches 174, 175 and 172, 173 respectively included in the primary and secondary telegraph circuits provide these circuits with additional over current protection. It is noted that the adjustable resistors 158 and 155 respectively included in the primary and secondary telegraph circuits are provided for the purpose of regulating the normal flow of current from the batteries 205 and 207, respectively, therein.

The protective relays R162 and R150 respectively included in the primary and secondary telegraph circuits are of the over-under current type. Specifically, in the event the current in the primary telegraph circuit rises above a predetermined value, the relay R162 operates its armature to close the contact 163, thereby to complete an obvious circuit for illuminating the supervisory lamp L128. Similarly, in the event the current in the secondary telegraph circuit rises above a predetermined value, the relay R150 operates its armature to close the contact 151, thereby to complete an obvious circuit for illuminating the supervisory lamp L127. On the other hand, in the event the current in the primary telegraph circuit falls below a predetermined value, the relay R162 restores its armature to close the contact 164, thereby to complete the circuit for illuminating the supervisory lamp L128. Similarly, in the event the current in the secondary telegraph circuit falls below a predetermined value, the relay R150 restores its armature to close the contact 152, thereby to complete the circuit for illuminating the supervisory lamp L127. In the event that the primary telegraph circuit is interrupted, the protective relay R160 restores to complete, at RA161, an obvious multiple circuit for illuminating the supervisory lamp L124 and for operating the alarm device A125. Similarly, in the event that the secondary telegraph circuit is interrupted, the protective relay R153 restores to complete, at RA154, an obvious multiple circuit for illuminating the supervisory lamp L123 and for operating the alarm device A125. The operation of the alarm device A125 may be arrested by operating the keys K157 or K156, depending upon which of the previously mentioned operating circuits is completed, the completed circuit being

indicated by the illumination of the supervisory lamps L124 and L123. Also, in the event the secondary telegraph circuit is interrupted, the protective relay R113 restores to complete, at RA115, an obvious path including the key K111 for short-circuiting the winding thereof and to complete, at RA114, an obvious circuit for illuminating the supervisory lamp L112. After the secondary telegraph circuit has been recompleted, the protective relay R113 may be reoperated by operating the key K111, thereby to interrupt the previously mentioned path for short-circuiting the winding thereof. Upon operating, the protective relay R113 interrupts, at RA115, an additional point in the previously mentioned path for short-circuiting the winding thereof and interrupts, at RA114, the previously mentioned circuit for illuminating the supervisory lamp L112.

In order to test the line conductors of the primary and secondary telegraph lines, in order to determine the presence of ground potential thereupon, an arrangement is provided which comprises the test relay R170, the supervisory lamp L126, and the keys K165, K166, K167 and K168, these keys being respectively associated with the line conductors C201, C301 and C202, C302, respectively, of the secondary and primary telegraph circuits 60 and 50. When one of these keys is operated, an obvious circuit is completed for energizing the test relay R170 in the event ground potential appears upon the corresponding line conductor of the telegraph circuit. Upon operating, the test relay R170 completes, at RA171, an obvious circuit for illuminating the supervisory lamp L126, the illumination of the supervisory lamp L126 indicating that the line conductor of the telegraph circuit corresponding to the operated key has ground potential thereon.

It is noted that the operator at the dispatcher station 100 may transmit a message over the primary and secondary telegraph circuits selectively or simultaneously and that the message may be transmitted thereover either manually or automatically, as desired. A message may be manually transmitted over the primary telegraph circuit by operating the telegraph key K101 in an obvious manner. Each time the primary telegraph circuit is interrupted at the telegraph key K101, the winding of the alarm device A107 is interrupted, thereby to cause the alarm device A107 to operate and tap out the code of the message being transmitted. Similarly, each time the primary telegraph circuit is interrupted, the printing magnet PM106 of the printer P102 restores, thereby to cause the armature 104 thereof to print a record of the message being transmitted on the moving tape 105. In the event that it is undesirable to have the alarm device A107 operate in accordance with the message being transmitted over the primary telegraph circuit, operation thereof may be arrested by operating the key K107, thereby to complete an obvious path for short-circuiting the winding of the alarm device A107.

A message may be manually transmitted over the secondary telegraph circuit by operating the telegraph key K102 in an obvious manner. Each time the secondary telegraph circuit is interrupted at the telegraph key K102, the winding of the alarm device A109 is interrupted, thereby to cause the alarm device A109 to operate and tap out the code of the message being transmitted. The first time the secondary telegraph circuit is interrupted, the protective relay R113

restores, thereby to complete the previously mentioned path for short-circuiting the winding thereof and to complete the previously mentioned circuit for illuminating the supervisory lamp L112. The relay R113 remains in its restored position until the conclusion of the transmission of the message over the secondary telegraph circuit.

A message may be manually transmitted over the primary and secondary telegraph circuits simultaneously by operating the telegraph key K117 in an obvious manner. Each time the telegraph key K117 is operated, an obvious circuit is completed for energizing the impulse relay R120, thereby to cause the latter relay to operate. Upon operating, the impulse relay R120 interrupts, at RA121, a point in the primary telegraph circuit and interrupts, at RA122, a point in the secondary telegraph circuit. Also, a message may be automatically transmitted over the primary and secondary telegraph circuits by initiating operation of the sender 118, thereby to control the circuit for energizing the impulse relay R120 in an obvious manner.

As previously noted, the winding of the printing magnet PM347 in the fire station 300 is normally included in the primary telegraph circuit. Accordingly, each time the primary telegraph circuit is interrupted, the printing magnet PM347 restores, thereby to cause the armature 346 thereof to print the message transmitted upon the moving tape 347. Also, it is noted that the winding of the printing magnet PM347 may be excluded from the primary telegraph circuit and included in the secondary telegraph circuit by operating the key K320. When the key K320 is operated, an alternative path is completed between the conductors C302 and C350 in the primary telegraph circuit excluding the winding of the printing magnet PM347. This path extends from the conductor C302 by way of the fuse 352, the contact 314 of the key K313, the winding of the alarm device A311, the contact 323 of the key K320, C356, the contact 332 of the key K330 and the fuse 339 to the conductor C350. Also, when the key K320 is operated, the winding of the printing magnet PM347 is included in the secondary telegraph circuit. The path for including the winding of the printing magnet PM347 in the secondary telegraph circuit extends from the conductor C301 by way of the fuse 340, the contact 337 of the key K335, C358, the contact 322 of the key K320, the winding of the printing magnet PM347, the contact 325 of the key K320, the winding of the alarm device A312, the contact 317 of the key K316 and the fuse 353 to the conductor C351. Thus, when the key K320 occupies its operated position, the printer P345 is operative to print the message transmitted over the secondary telegraph circuit. It will be understood that a printer is included in the position equipment 210 at the fire station 200 and in the position equipment at the other fire stations and that keys corresponding to the key K320 are included in the position equipment at the several fire stations, thereby selectively to control the association of the printers included in the position equipment thereat with the primary and secondary telegraph circuits in the manner explained above.

An arrangement is incorporated in the position equipment at each of the several stations which is operative selectively to complete alternative primary and secondary telegraph circuits by way of a common ground return connection in the

event a line conductor in the primary or secondary telegraph circuits extending between two of the stations is interrupted to cause the metallic primary or secondary telegraph loop circuits to be interrupted. For example, in the event the line conductor C302 included in the primary telegraph circuit and extending between the dispatcher station 100 and the fire station 300 is interrupted, neglecting for the present consideration the presence of the other fire stations disposed between the dispatcher station 100 and the fire station 300, the metallic loop circuit of the primary telegraph circuit is interrupted in an obvious manner. In order to reestablish communication over the primary telegraph circuit, the key K146 in the position equipment 110 at the dispatcher station 100 is operated, thereby to interrupt, at the contact 148 thereof, the connection between the line conductors C191 and C199 and to complete, at the contact 147 thereof, an obvious path for applying direct ground potential to the line conductor C191. Also, the key K313 in the position equipment 310 at the fire station 300 is operated, thereby to interrupt, at the contact 314 thereof, the connection between the winding of the alarm device A311 and the line conductor C302 and to complete, at the contact 315 thereof, an obvious path for applying direct ground potential to the winding of the alarm device A311. At this time an alternative primary telegraph circuit is completed including a ground return. This alternative circuit extends from a ground point by way of the contact 315 of the key K313 in the position equipment 310 at the fire station 300 by way of the previously traced circuit to the negative terminal of the battery 205, and from a ground point by way of the contact 147 of the key K146 in the position equipment 110 at the dispatcher station 100 by way of the previously traced circuit to the positive terminal of the battery 205, the ground points mentioned being connected together by a suitable conductor, such, for example, as the city water distribution system.

Similarly, it will be understood that in the event the line conductor C202 included in the primary telegraph circuit and extending between the dispatcher station 100 and the fire station 200 is interrupted, an alternative primary telegraph circuit including a common ground return connection may be completed by operating the control key K220 in the position equipment 210 at the fire station 200 and the key K186 in the position equipment 110 at the dispatcher station 100. In a similar manner, in the event the line conductor C350 included in the primary telegraph circuit and extending between the fire stations 200 and 300 is interrupted, an alternative primary telegraph circuit including a common ground return connection may be completed by operating the key K230 in the position equipment 210 at the fire station 200 and the key K330 in the position equipment 310 at the fire station 300. The alternative primary telegraph circuits completed incident to the operation of the keys in the position equipment at the several stations will be apparent from the foregoing example.

In a similar manner, it will be understood that alternative secondary telegraph circuits may be completed in the event the line conductors included in the secondary telegraph circuit and extending between the various stations are interrupted. For example, in the event the line conductor C301 included in the secondary telegraph circuit and extending between the dispatcher sta-

tion 100 and the fire station 300, neglecting for the present consideration the presence of the other fire stations disposed between the dispatcher station 100 and the fire station 300, an alternative secondary telegraph circuit may be completed by operating the key K182 in the position equipment 110 at the dispatcher station 100 and the key K335 in the position equipment 310 at the fire station 300. This alternative secondary telegraph circuit extends from a ground point at the contact 184 of the key K182 by way of the previously traced circuit to the positive terminal of the battery 207, and from a ground point at the contact 338 of the key K335 by way of the previously traced circuit to the negative terminal of the battery 207, the ground points mentioned being connected together by a suitable conductor. Similarly, it will be understood that in the event the line conductor C201 included in the secondary telegraph circuit and extending between the dispatcher station 100 and the fire station 200 is interrupted, an alternative secondary telegraph circuit may be completed by operating the key K136 in the position equipment 110 at the dispatcher station 100 and the control key K235 in the position equipment 210 at the fire station 200. In a similar manner, in the event the line conductor C351 included in the secondary telegraph circuit and extending between the fire stations 200 and 300 is interrupted, an alternative secondary telegraph circuit may be completed by operating the key K245 in the position equipment 210 at the fire station 200 and the key K316 in the position equipment 310 at the fire station 300. The alternative secondary telegraph circuits completed incident to the operation of the keys in the position apparatus at the several stations will be apparent from the foregoing example.

In the event the primary telegraph circuit 50 is completely interrupted due, for example, to the fact that both of the line conductors C202 and C302 included in the primary telegraph circuit and respectively extending between the dispatcher station 100 and the fire station 200 and the dispatcher station 100 and the fire station 300 are interrupted, it is desirable to transfer the telegraph key K101 and the printer P102 normally included in the primary telegraph circuit into the secondary telegraph circuit. This may be accomplished by operating the key K140 in the position equipment 110 at the dispatcher station 100. When the key K140 is thus operated, the secondary telegraph circuit extends from the positive terminal of the battery 207 by way of the previously traced circuit including the telegraph key K102 to the conductor C196, from the conductor C196 by way of the contact 142 of the key K140, C194, RA121, the winding of the alarm device A107, the telegraph key K101, the winding of the printing magnet PM106, C195, the contact 133 of the key K130 and the contact 144 of the key K140 to the conductor C197, the conductor C197 being connected by way of the previously traced circuit to the negative terminal of the battery 207. When the key K140 is thus operated, further points in the primary telegraph circuit are interrupted at the contacts 143 and 145 of the key K140. At this time the apparatus including the alarm device A107, the telegraph key K101 and the printing magnet PM106, which is normally included in series circuit relationship with the primary telegraph circuit, is included in series circuit relationship with the secondary telegraph circuit.

In the event the secondary telegraph circuit 60 is completely interrupted due, for example, to the fact that both of the line conductors C201 and C301 included in the secondary telegraph circuit and respectively extending between the dispatcher station 100 and the fire station 200 and the dispatcher station 100 and the fire station 300 are interrupted, it is desirable to transfer the telegraph key K102 normally included in the secondary telegraph circuit into the primary telegraph circuit. This may be accomplished by operating the key K130 in the position equipment 110 at the dispatcher station 100. When the key K130 is thus operated, the primary telegraph circuit extends from the positive terminal of the battery 205 by way of the previously traced circuit including the telegraph key K101 to the conductor C195, from the conductor C195 by way of the contact 131 of the key K130, C192, the winding of the protective relay R113, the telegraph key K102, the winding of the alarm device A109, RA122, the contact 134 of the key K130 and the contact 145 of the key K140 to the conductor C191, the conductor C191 being connected by way of the previously traced circuit to the negative terminal of the battery 205. When the key K130 is thus operated, further points in the secondary telegraph circuit are interrupted at the contacts 132 and 135 of the key K130. At this time the apparatus including the alarm device A109, the winding of the protective relay R113 and the telegraph key K102, which is normally included in series circuit relationship with the secondary telegraph circuit, is included in series circuit relationship with the primary telegraph circuit.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telegraph system, a sending station, a plurality of receiving stations, position equipment at each of said stations, a primary telegraph circuit including a source of current connecting the position equipment at said stations in series circuit relationship, said primary telegraph circuit including a number of primary telegraph lines arranged in series circuit relationship and respectively extending between adjacent ones of said stations, a secondary telegraph circuit including a source of current connecting the position equipment at said stations in series circuit relationship, said secondary telegraph circuit including a number of secondary telegraph lines arranged in series circuit relationship and respectively extending between adjacent ones of said stations, a common conductor extending between each two of said stations, the position equipment at adjacent ones of said stations being operable selectively to complete alternative primary and secondary telegraph circuits respectively excluding the primary and secondary telegraph lines extending between said adjacent stations and respectively including said common conductor extending between said adjacent stations, a sending device included in the position equipment at said sending station and adapted selectively to be operatively associated with said primary and said secondary telegraph circuits, and a receiving device included in the position

equipment at each of said receiving stations and adapted selectively to be operatively associated with said primary and said secondary telegraph circuits.

2. In a telegraph system, a sending station, a plurality of receiving stations, position equipment at each of said stations, a primary telegraph circuit including a source of current connecting the position equipment at said stations in series circuit relationship, said primary telegraph circuit including a number of primary telegraph lines arranged in series circuit relationship and respectively extending between adjacent ones of said stations, a secondary telegraph circuit including a source of current connecting the position equipment at said stations in series circuit relationship, said secondary telegraph circuit including a number of secondary telegraph lines arranged in series circuit relationship and respectively extending between adjacent ones of said stations, a common conductor extending between each two of said stations, the position equipment at each of said stations including primary and secondary switching apparatus respectively associated with said primary and said secondary telegraph circuits, the primary switching apparatus included in the position equipment at adjacent ones of said stations being operable to disconnect the primary telegraph line extending between said adjacent stations from said primary telegraph circuit and to complete an alternative primary telegraph circuit including said common conductor extending between said adjacent stations, the secondary switching apparatus included in the position equipment at adjacent ones of said stations being operable to disconnect the secondary telegraph line extending between said adjacent stations from said secondary telegraph circuit and to complete an alternative secondary telegraph circuit including said common conductor extending between said adjacent stations, a sending device included in the position equipment at said sending station and adapted selectively to be operatively associated with said primary and said secondary telegraph circuits, and a receiving device included in the position equipment at each of said receiving stations and adapted selectively

to be operatively associated with said primary and said secondary telegraph circuits.

3. In a telegraph system, a sending station, a plurality of receiving stations, position equipment at each of said stations, a primary telegraph circuit including a source of current connecting the position equipment at said stations in series circuit relationship, said primary telegraph circuit including a number of primary telegraph lines arranged in series circuit relationship and respectively extending between adjacent ones of said stations, a secondary telegraph circuit including a source of current connecting the position equipment at said stations in series circuit relationship, said secondary telegraph circuit including a number of secondary telegraph lines arranged in series circuit relationship and respectively extending between adjacent ones of said stations, the position equipment at each of said stations including primary and secondary switching apparatus respectively associated with said primary and said secondary telegraph circuits, the primary switching apparatus included in the position equipment at adjacent ones of said stations being operable to disconnect the primary telegraph line extending between said adjacent stations from said primary telegraph circuit and to complete an alternative primary telegraph circuit including a ground return connection extending between said adjacent stations, the secondary switching apparatus included in the position equipment at adjacent ones of said stations being operable to disconnect the secondary telegraph line extending between said adjacent stations from said secondary telegraph circuit and to complete an alternative secondary telegraph circuit including a ground return connection extending between said adjacent stations, a sending device included in the position equipment at said sending station and adapted selectively to be operatively associated with said primary and said secondary telegraph circuits, and a receiving device included in the position equipment at each of said receiving stations and adapted selectively to be operatively associated with said primary and said secondary telegraph circuits.
